UNITED STATES PATENT OFFICE.

JOHANNES T. SENTROP, JR., OF GRAND RAPIDS, MICHIGAN.

MOLD.

Application filed October 13, 1924. Serial No. 743,228.

To all whom it may concern:

Be it known that I, JOHANNES T. SENTROP, Jr., a subject of the Queen of the Netherlands, residing at Grand Rapids, in the county of 5 Kent and State of Michigan, have invented new and useful Improvements in Molds, of which the following is a specification.

The present invention relates to molds or forms for molding concrete beams, columns 10 and the like; and its object is, generally, to provide such molds improved in various respects hereinafter appearing; and more particularly, to provide such molds having separable members which may be readily assembled 15 and disassembled; and further, to provide improved means for holding a plurality of such molds and the members of each in such assembled position; and further, to provide improved separate members of such 20 molds; and further, to provide in such molds members which may be readily shortened or lengthened; and further, to provide such members which may be readily changed into different cross-sectional shapes. 25

These and any other objects hereinafter appearing are attained by, and the invention finds preferable embodiment in, the structure or structures hereinafter particularly described in the body of this specification 30 and illustrated by the accompanying drawings; in which:—

Figure 1 is a top plan view of molds or forms, partially sectioned longitudinally on a horizontal plane corresponding to line 35 1—1 of Figure 2;

Figure 2 is a longitudinal sectional view thereof taken on a vertical plane corresponding to line 2—2 of Figure 1;

Figure 3 is a transverse sectional view of 40 the same taken on a vertical plane corresponding to line 3—3 of Figure 2;

Figure 4 is a like view of the same, omitting certain extension pieces, and showing the dimensions of certain parts somewhat 45 variant from Figure 3;

Figure 5 is a transverse sectional view of the molds taken on a vertical plane corresponding to line 5—5 of Figures 2 and 6;

Figure 6 is a longitudinal sectional view

of one of the members of the mold taken 50 on a vertical plane corresponding to line 6—6 of Figure 5;

Figure 7 is a face view of a transverse part of another member of the mold;

Figure 8 is a top plan view thereof; 55

Figure 9 is a side edge view of the same;

Figure 10 is a transverse sectional view of another part of said member;

Figure 11 is a transverse sectional view of a telescoping pair of said parts; 60

Figure 12 is a side view of the end portion of one of the members of the mold;

Figure 13 is an end view of said member;

Figure 14 is a side view of telescoping parts of one of the members of the mold; 65

Figure 15 is a transverse sectional view of one of said parts, showing its position lower than in Figures 10 and 11;

Figure 16 is a face view of an end member of the mold; 70

Figure 17 is a top plan view thereof;

Figure 18 is a side edge view of the same; and

Figure 19 is a side view of an end portion of the mold, certain parts together with the 75 material formed in the mold being shown in central vertical section.

In the accompanying drawings a plurality of molds are shown adapted for molding concrete and the like into structural forms, such as floor beams, columns and the like.

These molds are assembled side by side on a level floor, which desirably comprises spaced apart strips 1 suitably supported as by posts 2. The several members of each mold, some of which members are common to adjacent molds, comprises the following:

The inner member, designated generally 3, has a thin sheet metal part 4 curved or bowed in transverse section, and desirably 85 bendable to vary such curvature. This inner member 3 has also a transverse supporting part 6 contacting the inner surface of

the curved metal part 4 and comprising portions or halves 7, 8 lying in approximately 90 the same vertical planes, their inclined edges 9 contacting each other. These halves are 95 detachably secured together by suitable

means as by the threaded bolt 10 passing through openings therein and carrying a wing nut 11. It will be seen that when this nut is tightened the halves of this part 6 are brought into edgewise contact with the inner surface of the sheet metal part 4 of this mold member 3; and when said nut is loosened the halves 7, 8 may be readily separated from the metal part 4 and removed therefrom.

The longitudinal edges of the sheet metal part 4 are desirably provided with cross-sectionally-angular metal strips 12 whose flanges 13 may be secured, as by screws 14, to the upper sides of the wooden strips 15 as shown in Figures 5, 10 and 11; or they may be thus secured to the under sides of said strips, or laid under the lower or intermediate members 16 of the mold as shown in Figure 15. When thus positioned, it will be seen that a cross-sectionally smaller open space 17 is made in the molded work than is made when said flange is positioned above the floor 1 as seen in Figures 5, 10 and 11. The outer member, designated generally 18, of the mold may be, as shown in the views, common to adjacent molds. This member comprises side parts 19, preferably of sheet metal convexing angularly outwardly and secured to upper and lower wooden strips 20, 21, which are spaced apart by blocks 22. When it is desired to mold beams, columns and the like having a larger dimension, extension pieces 24 may be secured to the outer surface of one or both of these strips, as shown in Figure 5. This outer member 18 of the mold may be provided with end pieces 25 secured as by screws 26 to the end blocks 22. The intermediate members 16 of the mold rests upon said floor between and contacting the inner member 3 and the outer member 18 of the mold as shown in Figure 5. A plurality of the molds are assembled side by side on the floor 1, as indicated in the views, and are held in contact with each other by suitable means, as the nails 30 driven upwardly through the floor strips 1 and into the lower edges of the outer members 18 of the molds or into their lower extension pieces 24, and also by strips 31 extending above the molds and transversely thereof and secured, as by nails 32, to the upper edges of said outer members 18 or their upper extension pieces 24. End members 33 of the molds are particularly shown in Figures 16, 17 and 18, comprising portions or halves 34, 35 having inclined contacting edges 36, similar to such edges of the halves of the transverse supporting part 6 and similarly connected together by a bolt 37 and nut 38. The corners of these end members are shown notched at 39 in Figure 16 to receive metal reinforcing rods 40 for the concrete work. Spaced inwardly from these end members 33, are transverse

supporting parts 6, between which and the adjacent end members 33 the concrete 41 is poured as indicated in Figure 19. A bottom plate 42 of the mold is placed between the end member 33 and transverse supporting part 6. The mold may be divided longitudinally by a strip 43 resting on the upper surface of the curved metal part 4 as indicated in Figure 4, to thus provide molded work suitable for window or door jambs and the like.

As indicated in Figures 11 and 14, the curved metal parts 4 of the mold's inner member 3 may be arranged to telescope each other to provide a mold of greater or less length. This telescoping action may be readily provided for, when the strips 15 are omitted entirely or are shortened sufficiently at their ends.

The reinforcing rods 40 at the upper and lower sides of the work may be formed continuously as indicated in Figure 17, thus providing a bight portion 50 which may be utilized as anchoring members for the ends of the concrete beams or columns.

As indicated at the right hand side of Figure 5, the outer members 18 may be positioned with their thicker portions downward; or, as seen at the left hand side of said view, they may be positioned with their thicker portions upward; so that beams or columns thicker at one side or the other may be thus molded as may be desired.

The invention being intended to be pointed out in the claims, is not to be limited to or by details of construction of the particular embodiment or embodiments thereof illustrated by the drawings or hereinbefore described.

I claim:

1. In a mold: an inner member comprising a plurality of longitudinally-telescoping upwardly-bowed portions; an outer member; an intermediate member contacting on its opposite sides said inner and outer members respectively; means for detachably securing said members in said contacting position.

2. In a mold: an inner member having a cross-sectionally-bowed part and a supporting part therein extending transversely thereof and comprising portions having inclined meeting edges, and means for releasably holding said edges in contacting position.

3. In a mold: an end member comprising portions having inclined meeting edges, and means for releasably holding said edges in contacting position, said member having notches in its outer edges adapted to receive concrete-reinforcing rods.

4. In a mold, an outer member comprising: spaced strips extending in said member's longitudinal direction; blocks intermediate said strips and secured thereto;

sheet sides secured to the opposite sides of the strips.

5. In a mold, an outer member comprising: spaced strips extending in said member's longitudinal direction; blocks intermediate said strips and secured thereto; sheet sides secured to the opposite sides of

the strips; an extension piece detachably secured to the outer surface of one of said strips.

In testimony whereof I have hereunto set my hand at Grand Rapids, Michigan, this 10th day of October, 1924.

JOHANNES T. SENTROP, JR.
